CLAIM

The ornamental design for a bottle case as shown and described.

DESCRIPTION

FIG. 1 is a front elevation view of a first embodiment of our new design for a bottle case.

FIG. 2 is a back elevation view thereof.

FIG. 3 is a top plan view thereof.

FIG. 4 is a bottom plan view thereof.

FIG. 5 is a left elevation view thereof.

FIG. 6 is a right elevation view thereof.

FIG. 7 is a top right perspective view thereof.

FIG. 8 is a bottom left perspective view thereof.

FIG. 9 is a front elevation view of a second embodiment of our new design for a bottle case.

FIG. 10 is a back elevation view thereof.

FIG. 11 is a top plan view thereof.

FIG. 12 is a bottom plan view thereof.

FIG. 13 is a left elevation view thereof.

FIG. 14 is a right elevation view thereof.

FIG. 15 is a top right perspective view thereof; and,

FIG. 16 is a bottom left perspective view thereof.

The broken lines illustrate portions of the bottle case that form no part of the claimed design.

1 Claim, 12 Drawing Sheets
